COMBINED CURB AND SEWER

Herman G. Moselowitz, New Brunswick, N. J.

Application October 10, 1944, Serial No. 557,962

12 Claims. (Cl. 94—31)

This invention relates to improvements in roadway drains and has particular reference to a combined curb and sewer.

One of the important features of the invention resides in a combined curb and sewer construction for roadways and airfield runways in which the same is formed of a series of units laid and connected end to end, the units being substantially ovate shape in cross section to facilitate easy handling during transportation and when placed in position upon a job.

Another feature of the invention is to provide a combined curb and sewer adapted to parallel the sides of a roadway or airfield runway which has an open top disposed flush with the surface of the ground, the open top being covered by removable grating sections to facilitate easy access to the interior of the sewer for cleaning purposes, and which grating serves as a sidewalk when the curb and sewer is used along roadways.

Another feature of the invention is to provide a combined curb and sewer unit which receives and carries away water drained from a roadway or airfield runway, there being means in certain units for sub-surface drainage when required.

A further feature of the invention is the provision of a drainage sewer unit in which the flow trough therein is rounded on an arc struck from a single axis to induce the free flow of water and solids therethrough and to enable thorough cleaning should silt accumulate therein.

Other novel features of the invention will become apparent as the following specification is read in conjunction with the accompanying drawings, in which,

Figure 1 is a perspective view of a curb and sewer constructed in accordance with my invention, one of the cover sections being separated from its body section.

Figure 2 is a vertical transverse sectional view taken through an airplane runway equipped with the improved curb and sewer construction.

Figure 3 is an enlarged vertical transverse sectional view taken on the line 3—3 of Figure 1.

Figure 4 is a detail vertical sectional view through the joint between two sewer and curb units.

Figure 5 is a vertical transverse sectional view taken through a roadway equipped with the improved curb and sewer construction.

Figure 6 is an enlarged vertical transverse sectional view through the curb and sewer construction showing the curb drainage inlet.

Figure 7 is a view similar to Figure 6 but showing the sub-surface drainage openings.

Figure 8 is a perspective view illustrating a modified form of curb and sewer unit.

Figure 9 is a perspective view of a further modified form of curb and sewer unit.

Figure 10 is a fragmentary top plan view with parts broken away in section of a modified form of cover for the curb and sewer unit.

Referring to the drawings by reference characters and at present to Figures 1 to 7 thereof, the numeral 10 designates a curb and storm sewer unit constructed in accordance with my invention. The unit 10 is pre-cast of concrete or other strong plastic substance and includes a trough shape body 11 of a suitable predetermined length, and a cover in the form of a grating 12 for closing the open top of the body 11.

The body 11 is substantially ovate or horse-shoe shape in cross section and comprises a bottom wall 13 and upwardly curved side walls 14—

20 14. The exterior of the bottom wall is flat as at 15 to facilitate the setting of the unit in an upright position for use and during storage and shipment. The top of the body 11 is also flat as at 15a.

The inner surface 16 of the bottom wall 13 is rounded on an arc struck from a single axis and said surface 16 joins with the upwardly converging concavely curved inner surfaces 17—17 of the respective side walls 14—14. The space defined by the inner surfaces 16 and 17—17 constitutes a water flow passage 18 which extends the length of the body 11.

The inner side of the side walls 14—14 adjacent the top thereof are provided with opposed horizontal shoulders or ledges 19—19 which extend lengthwise of the body. One of the ends of the shoulders 19—19

35 terminate short of one end of the side walls 14—14 while the other ends thereof extend beyond the other end of the body and join the free ends of a male coupling member in the form of a coupling flange 20.

The coupling flange 20 conforms to the cross sectional shape of the passage 18 and is coextensive with one end of the body 11. The other end of the body 11 has its side and bottom walls formed with a continuous internally reduced female portion 21 which is parallel to the flange 20 and in alignment therewith. In use, the units 10 are placed end to end with the flange 20 of one unit fitting into the reduced portion 21 of a next adjacent unit and with the adjacent ends 40 of the bodies 11 of the units in abutting relation as best illustrated in Figure 4.

When the unit 10 is constructed of cement, the walls thereof are preferably reinforced by metal wire or bars 22.

55 Certain of the curb and sewer units 10 are pro-

vided with sub-surface drain openings 23 in the bottom and lower portions of the side walls thereof. The units having the sub-surface drain openings are placed along the length of an installation wherever necessary.

When the units 10 are used along a roadway as a combined curb and sewer, the inwardly facing side wall 14 thereof is provided with one or more drainage inlets 24, the same being located at the surface level of the roadway as illustrated in Figure 6.

In Figures 2 and 3 of the drawings I have illustrated my invention in use along opposite sides of a concrete airfield runway A, the bottom of the units resting upon the sub-grade B. The units are connected together in end to end relation and parallel the sides of the runway A with their top surfaces flush with the runway A. The gratings 12 close the open tops of the bodies of the units and seat upon the shoulders 19-19. Each grating 12 is formed of concrete or other plastic material and comprises an elongated slab-like body 25 having spaced drain openings 26 therein. The grating is of a length equal to that of the body 11 on which it fits, the ends of the slab body terminating in reduced offset flanges 27 and 28. When in position, the flange 28 of one grating overlies the flange 27 of the next adjacent unit whereby to provide a lapping joint between the ends of adjacent gratings. Water which may drain from the runway A to opposite sides thereof will flow onto the gratings 12 and pass through the drain openings 26 into the passageway 18, from where it flows to a main sewer or pass out through the sub-surface drain openings 23 into the sub-grade B.

In Figures 5, 6 and 7, I have illustrated my invention as being installed along the sides of a street or roadway C, wherein the upper portions of the bodies of the units 10 rise above the adjacent surface level thereof to form a curb. The drain inlets 24 are flush with the adjacent surface level of the roadway to receive water which may drain therefrom, said water entering the passageway 18 and being carried away to a main sewer or for escape through the sub-surface drainage openings 23. In this use, the grating sections 12 may be used as a walk for persons walking along the roadway.

In Figure 8 of the drawings, I have illustrated a slight modified form of my invention, wherein one end of the top of the body 11 is closed as at 29. The closed end of one unit fits against the top open end of a next adjacent unit to form a rectangular opening 30 for receiving a similar shaped grating 31.

In Figure 9 of the drawings, there is illustrated a further modification in which both ends of the open top of the body 11 of each unit is closed as at 35-35 to provide a rectangular shaped opening 33 for receiving a similar shaped grating (not shown).

When the units are employed along the sides of roadways, the gratings may be in the form of solid covers to provide a smooth surface on which to walk.

In Figure 10 there is illustrated a still further modified form in which the bodies of the units 11 are similar to those shown in Figure 1, but in which solid covers or slabs 36 cover the open top thereof. The end of each slab 36 is formed with a notch 37 and when the notches of two adjacent slabs are in complementary confronting relation to each other, a drain opening 38 is formed through

which water may drain into the passageway 18.

When the units 11 are laid end to end on a grade in the direction of the intended flow of water therethrough, it will be understood that the passageways 18 are self cleaned for any solids will be washed away with the drain water for there are no corners along the passageway in which solids may be trapped. Should manual cleaning be necessary, the covers or gratings are removed from the tops of the bodies 11, thus permitting free access to the passageway 18.

Due to the ovate shape of the body 11 of the unit, the same may be easily handled by rolling the same which expedites the transportation of the units and the placing of the same in position for use.

While I have shown and described what I consider to be the most practical embodiments of my invention, I wish it to be understood that such changes in construction, design and materials as come within the appended claims may be resorted to if desired without departing from the spirit of the invention.

Having thus described the invention, what I claim as new and desire to secure by Letters Patent is:

1. A combined curb and drain comprising a reinforced concrete elongated hollow body of horse-shoe shape in cross section having a rounded inner bottom wall and curved upwardly converging opposed side walls, one of said side walls having an inwardly inclined drain inlet therein above the bottom wall thereof, opposed parallel ledges provided on the inner sides of the side walls adjacent the top thereof, and a slab-like concrete grating seated on the ledges and closing the top of said body and disposed flush with the top thereof, the body also having drain openings from the interior adjacent the bottom and additional inlets in its top.

2. A combined curb and drain unit comprising a rigid elongated body of concrete or like plastic material being ovate shape in cross section having flat top and bottom surfaces, said body having a flow passage therein extending lengthwise thereof from end to end, the inner surface of the bottom of the flow passage being curved on an arc struck from a single axis, one of the side walls of the said body above the bottom of the passage having inlet surface drain openings therein, said body also having subsurface outlet openings leading outwardly and downwardly adjacent the bottom of said passage.

HERMAN G. MOSELOWITZ.
